ATTORNEY.

UNITED STATES PATENT OFFICE.

HERMON L. POWELL, OF UTICA, NEW YORK, ASSIGNOR TO REMINGTON ARMS COMPANY, OF ILION, NEW YORK.

EJECTOR FOR FIREARMS.

SPECIFICATION forming part of Letters Patent No. 732,891, dated July 7, 1903.

Application filed May 2, 1903. Serial No. 155,239. (No model.)

To all whom it may concern:

Be it known that I, HERMON L. POWELL, of Utica, in the county of Oneida and State of New York, have invented certain new and useful Improvements in Ejectors for Firearms; and I do hereby declare that the following is a full, clear, and exact description of the invention, which will enable others skilled in the art to which it appertains to make and use the same, reference being had to the accompanying drawings, and to the figures of reference marked thereon, which form part of this specification.

The object of my invention is to provide an improved ejector mechanism for firearms which provides means for positively starting the shell from the barrel-chamber and thereafter expelling it and which is simple in construction and reliable in operation.

In the drawings, Figure 1 shows a portion of a firearm, partially in section, showing my improved ejector mechanism, the arm being shown in closed position. Fig. 2 shows a portion of the same parts shown in Fig. 1 with the arm in partially-open or broken-down position. Fig. 3 shows also substantially the same parts with the arm entirely open or broken down. Fig. 4 shows a section taken on line A B of Fig. 3. Fig. 5 shows diagram of a hammer-sear and operating-springs employed in the construction. Fig. 6 shows a side elevation, and Fig. 7 an edge view, of the starting-lever.

Referring to the reference-figures in a more particular description, 1 indicates the frame of the firearm, which includes, among other features, the breech-up shoulder 2 and a forward extension carrying the joint-pin 3.

4 is the barrel, provided with the usual barrel-lug 4, engaging on the joint-pin 3. In a longitudinal opening in the barrel-lug there is provided the sliding ejector, consisting of the slide or stem portion 5 and the head portion 6, adapted to engage the rim of a shell in the barrel. The ejector is secured in position by a pin 8 passing transversely through the barrel-lug and engaging in a slot or recess in the under side of the slide 5, permitting a limited movement of the ejector. Mounted on a common pivot 9 in the barrel-lug is the starting-lever 10 and the ejector-hammer 11.

One arm of the starting-lever 10 is adapted to engage with the rear end of the ejector-slide 5, while the other arm is adapted to be engaged by an inwardly-projecting pin 12, extending through one of the walls of the forwardly-projecting portion of the frame, it being understood, of course, that this forwardly-extending portion is recessed to receive the barrel-lug when the arm is closed. The ejector-hammer 11 is operated by the spring 13, secured on the under side of the barrel-lug, and is held in checked or retracted position by the sear 14, mounted on a pivot 15 in the barrel-lug. One end of the sear 14 projects under the joint-pin 3 and is adapted to engage, when the arm is open, with a wall of the frame and be thereby operated.

16 is the sear-spring, which operates to throw the sear into engagement with the hammer when it is not forced to its open position. A catch 16^a is provided for securing the gun in closed position, which catch is operated in the usual manner by the top lever 17.

In operation starting with the arm in the position shown in Fig. 1 as the gun is broken down after withdrawing the catch 16^a by operating the lever 17 the pin 12 comes into engagement with the starting-lever and forces the ejector toward its open position. When the operation has proceeded far enough, the arrangement is such that the sear engages with the wall of the frame and is thereby tripped, releasing the hammer 11, which under the impulse of the spring 13 strikes the rear end of the ejector-slide with a blow, thereby instantly expelling the shell. In closing the arm the ejector engages on the breech-up shoulder 2 and is caused back into its closed position, and at the same time the hammer 11 and the starting-lever 10 are also forced back into the positions in which they are shown in Fig. 1.

What I claim as new, and desire to secure by Letters Patent, is—

1. The combination in a breakdown firearm of the frame, barrel and barrel-lug jointed to the frame, a sliding ejector mounted in the barrel-lug, a starting-lever and an ejector-hammer both pivoted in the barrel-lug and adapted to operate on the ejector, a projection on the frame to engage and operate the starting-

lever, a sear operating to secure said hammer and adapted to engage the frame adjacent to the joint-pin and a spring for operating said hammer, substantially as set forth.

- 5 2. The combination in a breakdown firearm of the frame and barrel having a barrel-lug jointed to the frame, a sliding ejector mounted in the barrel-lug, a starting-lever and an ejector-hammer pivoted on a common pivot in the barrel-lug and adapted to operate on the ejector, a projection on the wall of the frame adapted to engage and operate the starting-lever in the opening operation, a sear adapted to secure said hammer having an arm

projecting under the joint-pin and adapted to be engaged by the frame, a spring for operating the hammer and a shoulder on the frame adapted to engage the ejector and reset the ejector and said operating mechanism, substantially as set forth.

In witness whereof I have affixed my signature, in presence of two witnesses, this 25th day of April, 1903.

HERMON L. POWELL.
